UNITED STATES PATENT OFFICE.

GEORGE F. VOIGHT, OF OAKLAND, CALIFORNIA.

WALL CONSTRUCTION.

Application filed December 1, 1922. Serial No. 604,389.

To all whom it may concern:

Be it known that I, GEORGE F. VOIGHT, a citizen of the United States, residing at Oakland, in the county of Alameda and 5 State of California, have invented new and useful Improvements in Wall Construction, of which the following is a specification.

My invention relates to improvements in wall construction particularly adapted for 10 frame buildings employing a wall covering of sheathing boards secured to the framework of the building and upon the outer side of which is disposed a coating of cement or plaster reinforced with a metal 15 grill; and one of the objects of the invention is the provision of furring units for securing the grill to the sheathing boards and furring it a proper distance outwardly therefrom.

A further object of the present invention 20 is the provision of furring units embodying a pair of oppositely disposed cooperable members over and against which the reinforcing grill is stretched, and between which members a fastening staple or nail is 25 adapted to be driven for securing the grill to the sheathing boards, the nail being operably drivable into the sheathing boards to an extent whereby no portion of it will project outwardly beyond the face of said members where it would be liable to be engaged 30 by the plasterers' trowel and interfere with the proper operation thereof when applying the plastic material to the reinforcement.

With the foregoing and still further objects and purposes in view which will appear as the description proceeds, my invention resides in the combination and arrangement of parts and in the details of construction hereinafter described and claimed, it 40 being understood that changes in the precise embodiment of the invention herein disclosed can be made within the scope of what is claimed without departing from the spirit of the invention.

45 In the accompanying drawings—

Figure 1 is a view in elevation of a portion of a wall embodying my invention, but not showing the cement coating;

Figure 2 is a plan view of one of the furring units;

Figure 3 is a side elevation of one of the furring units;

Figure 4 is a longitudinal sectional view on line 4—4, Fig. 2;

55 Figure 5 is a cross section on line 5—5, Fig. 2;

Figure 6 is a cross section on line 6—6, Fig. 2;

Figure 7 is a sectional view approximately on line 7—7, Fig. 1, also showing a section 60 of plastic composition in the immediate rear of the furring unit;

Figure 8 is a perspective view of one of the furring units;

Figure 9 is a perspective view of one of 65 the furring units in a modified form;

Figure 10 is a plan view of one of the units in its modified form; and

Figure 11 is a view on line 11—11, Fig. 10.

Referring to the drawings in detail, 70 throughout which like reference characters designate like parts—

The numeral 12 designates a section of a sheathing board as secured to the outer side of the wall of the building, upon the outer 75 side is disposed builders' paper 13. (While the builders' paper 13 is shown and described as forming part of the wall structure to which my device is applied, it is not essential for the proper application thereof, 80 and may, therefore, be entirely eliminated and the plastic material applied directly to the sheathing boards 12.)

At regular intervals along the face of the paper 13, preferably in staggered order, are 85 disposed furring units 14, which comprise, each, a rear sill 15 adapted to seat against the paper 13 and provided at either end with risers 16, which support one end of laterally spaced apart grill supporting bars 17, the 90 opposite ends of which bars supported by risers 19, the lower ends of which terminating in sills 18, the latter adapted to seat against the paper 13 and are provided at the free ends with prongs 20, which are adapted 95 to be driven through the paper into the sheathing boards as far as the sills 18 permit them to go. The furring units 14 are formed, preferably, so as to describe a closed loop, of which the sills 15 form the 100 rear ends, the sills 18 the front ends, and the bars 17 the sides. I prefer, also, to so form the front sills 18 that they will project forwardly beyond the bars 17 with their free ends converging so as to bring the prongs 105 20 into relative close proximity, whereby the prongs may be jointly engaged by a hammer and both driven by the same blows thereof.

The free ends of the sills 18 being extended forwardly of the bars 17 principally for the 110 purpose of providing ample room for the hammer so that the hammer may not acci-

dentially strike the bars while driving the prongs 20. (In order to make clear the construction of the units 14, I will here state that in the description the outer or free ends of the sills 18 are to be taken as forming part of the heads of the prongs 20.)

Across the furring units 14 and engaging the bars 17 is disposed a metal grill 21, which in the present instance comprises ordinary poultry-netting embodying a plurality of inter-twisted wires 22 forming hexagonal meshes 23.

Cooperable with each of the furring units 14 is a fastening staple 24, which is disposed intermediate the beams 17 of the unit and straddles one of the wires 22 from the outer side thereof and is driven into the board 12, through the paper 13, until its head 26 is approximately on a line with the outer surface of the bars 17 and the wire 22 drawn down slightly below the face of the beams (see Figs. 1 and 7).

It is obvious that the construction above set forth provides an outer surface for the reinforcing grill free from any metal projections that interfere with the proper operation of the trowel in the application of the plastic material.

27 designates the plastic composition, which is spread on the paper 13 and on and around the furring units 14 and the grill 21. Said furring units and grill forming the reinforcement for the plastic composition.

In Fig. 1, the numeral 28 designates portions of the grill formed by twisting two wires together.

It is obvious from the drawings that the furring units 14 may be constructed from suitable wire, preferably out of what is known as nail wire.

In the modified form of the invention, shown in Figs. 9, 10 and 11 of the drawings, I substitute a sheet metal strip for the wire and bend this flat-ways into a loop similar in form to the preferred form of unit. One of the edges of which sheet metal unit being adapted to seat against the paper 13 and the other edge to engage and support the grill wires. The free ends of the loop being

formed with spurs 30, which are adapted to be driven into the sheathing boards for the units thereto. The several members forming the sides and ends of the modified form of the unit may be provided with openings 29, into which some of the plaster material may be forced to provide proper clinching therefor.

I claim:—

1. A furring unit having laterally oppositely disposed wire supporting bars having one end unitarily connected together, one of said bars having a fastening prong.

2. A furring unit having a pair of laterally oppositely disposed wire supporting bars, a connection between corresponding ends of said bars, and fastening prongs on the other ends of said bars.

3. A furring unit comprising two staple-like sections disposed along side of each other, one end of said sections unitarily connected together, and means on said unit adapted for securing it to a support.

4. A furring unit having a fastening prong at one end for securing it to a sheathing board and having a pair of laterally spaced apart bars cooperable for engaging and supporting a reinforcing grill at a distance outwardly from said board.

5. A plurality of furring units adapted to be secured to a sheathing board, each of said units comprising sills supporting outstanding bars adapted for receiving and supporting a reinforcing grill, and a fastening nail disposed along opposed sides of said bars and adapted to be driven a distance in said board for securing the grill thereto.

6. In means of the character described, a furring unit embodying a length of wire bent double thereby disposing the free ends of said wire at the same end of the unit, sills at one end of the unit, and laterally spaced apart supporting bars having one end supported by said sills.

In testimony of the foregoing being my own, I have hereunto affixed my signature this 24th day of November, 1922.

GEORGE F. VOIGHT.
